UNITED STATES PATENT OFFICE.

WALTER H. HIMES, OF PITTSBURGH, PENNSYLVANIA, ASSIGNOR TO WESTINGHOUSE ELECTRIC & MANUFACTURING COMPANY, A CORPORATION OF PENNSYLVANIA.

CENTRIFUGAL DRYING MACHINE.

Application filed July 19, 1921. Serial No. 486,005.

My invention relates to centrifugally operated drying machines and it has particular relation to means for driving apparatus of the character indicated. It pertains to the subject matter of my copending applications, Serial Nos. 477,753 and 723,478, filed June 15, 1921, and July 1, 1924, respectively.

One object of my invention is to provide a mechanism whereby a vertically disposed spindle may be driven by a horizontally disposed motor by means of a direct connected belt, and whereby the possibility of such belt becoming disengaged from its operative position is avoided.

Another object of my invention is to provide means for accomplishing the aforementioned object which will in nowise retard the operation of the machine during its normal operation.

Heretofore, it has been customary to start centrifugally operated drying machines by rotating the same manually in order to start the clothes container before energizing the motor or at the instant of energization thereof. No means has been provided for preventing rotation of the basket in other than the proper direction. As a result, an inexperienced operator will very frequently rotate the basket in the direction opposite to that in which the motor tends to drive it. In such instances, the motor must first stop the rotation of the clothes container and subsequently start it in the reverse direction. This is objectionable as there is a possibility of overheating the motor seriously during the prolonged starting period.

Briefly, my invention consists of driving a vertically disposed centrifugal extractor from an electrical motor by means of a quarter-turn belt and providing a centrifugally actuated pawl mechanism which is operative only at relatively slow speeds to prevent rotation of the extractor mechanism in the direction which would tend to displace the aforementioned quarter-turn belt.

In the accompanying drawings,

Figure 1 is a cross-sectional view of a centrifugal extractor constructed in accordance with my invention, and

Fig. 2 is a sectional view taken along the line II-II of Fig. 1.

In the drawings, I show a supporting structure comprising a base member 3 and a housing 4 supported thereon by means of

an intermediate structure 5. Within the housing 4 is disposed a rotatable perforated clothes basket or container 6 mounted upon a vertically disposed shaft 7, the lower end of which is supported by means of a thrust bearing 8. The end of the shaft 7 is enclosed within a bearing sleeve 9. The sleeve 9 is disposed within an annular bearing housing 10, the lower end of which supports the thrust bearing 8, and which is mounted upon the portion 3 of the supporting structure by means of annular members 11 of resilient material. The upper end of the housing 10, which is stationary with respect to the supporting members 3, is provided with a ratchet wheel 12, the immediately adjacent portion 13 of which is tapered, for reasons to be hereinafter set forth.

Upon the shaft 7 is mounted a cylindrical housing 14 which encloses the sleeve 9 and the housing 10 and which has an enlarged portion 15 that constitutes a pulley. A horizontally disposed motor 16 is mounted upon the supporting structure 3 and is adapted to drive the shaft 7 by means of the pulley 15 through an endless belt 17. It will be observed that the motor is horizontally disposed whereas the member 14, which is driven thereby, moves about a vertical axis so that the belt connecting these two members must be of the character known as the quarter-turn belt. Any belt must be so disposed that the direction of motion of each tangent of belt is in the plane of rotation of the pulley which it engages. On disengaging from the pulley, the belt may lead out of this plane without interfering with proper functioning of the same. It is possible to so dispose two pulleys in different planes as to meet the above requirements provided the belt moves in one direction only. If the belt is operated in the reverse direction without readjusting the positions of the pulleys it will immediately roll off the pulleys. A belt of this type will tend to move into alignment with that portion of the driving pulley by means of which the pull is exerted upon the belt. This action necessitates that the belt be driven in one direction only, since, if it is driven in the opposite direction it will move off the pulley.

In order to prevent movement of the shaft 7 and its associated belt 17 in the wrong

2
direction, I provide within the housing 14 a pawl member 19 pivotally mounted upon a pin 20 and held normally in engagement with the ratchet wheel 12 of the housing 10 5 by means of a spring 21. The portion 13 of the ratchet wheel 12 is tapered for the following reason:

In assembling the machine, when the shaft 7, together with its associated ratchet wheel 12, is moved upwardly into the member 14, 10 the inclined portion 13 will serve as a guide to the pawl 19 and move it into engagement with the ratchet wheel. The spring 21 is of such resiliency that, when the basket 6 is 15 rotated at a relatively high speed, the pawl 19 will move outwardly out of engagement with the ratchet wheel 12, by centrifugal force, thus removing any drag or noise therefrom during normal operation. A pin 20 22 serves to prevent the pawl 19 from moving, under the influence of centrifugal force, to such position as to injure the spring 21. A pin 23 also serves to prevent the pawl 19 25 from moving inwardly beyond the point at which the inclined surface 13 would engage it.

From the foregoing description, it will be apparent that I have provided a device which will prevent the improper rotation 30 of the rotatable member, which if permitted, would displace the belt and result in a cessation of operation of the machine, such improper rotation might also injure the motor, as described. Also, it will be apparent that 35 the device whereby this result is accomplished will not interfere with the normal operation of the machine in any respect whatsoever and will become effective only at relatively low rates of speed and when the 40 clothes container is motionless. A further advantage obtained by my construction is that the assembly thereof is materially facilitated by tapering the upper portion of the ratchet wheel, which, if of the usual 45 type, would materially complicate assembly

thereof on account of the location of the pawl member.

While I have shown but a single embodiment of my invention, further changes and modifications may be made without departing from the spirit and scope thereof, and I desire, therefore, that only such limitations shall be placed thereon as are imposed by the prior art or are specifically set forth in the appended claims.

What I claim as my invention is:

1. In a centrifugal drying machine, a rotatable shaft having a housing member mounted thereon, a stationary bearing member surrounding said shaft and extending 60 within said housing member, said bearing member being provided with a ratchet wheel, and a spring-pressed pawl mounted within said housing member and adapted to co-operate with said ratchet wheel.

2. In a centrifugal drying machine, a rotatable shaft having a housing member mounted thereon, a stationary bearing member surrounding said shaft and extending within 70 said housing member, said bearing member being provided with a ratchet wheel, and a centrifugally actuated spring-pressed pawl mounted on and within said housing member and adapted to engage said ratchet wheel during relatively low-speed operation only.

3. In a centrifugal drying machine, a rotatable shaft having a housing member mounted thereon, a stationary ratchet wheel member disposed within said housing member, said ratchet wheel being provided with 80 an integral tapered portion immediately adjacent thereto, and a spring-pressed pawl mounted within and upon said housing member and adapted to co-operate with said ratchet wheel.

In testimony whereof, I have hereunto subscribed my name this 6th day of July, 1921.

WALTER H. HIMES.
